UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER BOX OR THE LIKE.

Application filed July 19, 1927. Serial No. 266,970.

This invention relates to improvements in paper boxes.

In the accompanying drawings which serve for illustrating the invention:

5 Fig. 1 is a plan view of the box blank;

Fig. 2 is a plan view of the box in knocked-down assembly;

Fig. 3 is a perspective view of the box closed;

10 Fig. 4 is a perspective view of the box open;

Fig. 5 is a cross sectional view of the box closed;

Fig. 6 is a cross sectional view of the box open;

15 Fig. 7 is a view illustrating a modification.

The objects attained in the invention consist in; first, a paper box adapted for low cost production; second, a display box in which the bottom end flaps are turned upward over the side end flaps, tucked in and compressed between the top and side end flaps by the contents of the box; third, a display box in which the inner face of the lid is presented for printing on the same side 20 of the box blank as the outer faces of the box; fourth, a display box in which the wing flaps of the lid are retained interlocked with the body of the box as the lid is opened and closed.

25 30 As to the first and third objects attained in the invention—low cost production—the box is so arranged that all the printing on the lid and body of the box is on the same side of the box blank. Thus box stock coated or finished on one side only, and printing on one side only, are required, which permits of using cheaper box stock, and reduces the production time, thus resulting in substantial savings in material and production costs. In 35 40 the common box of the same type the box blanks require printing on both sides and box stock coated or finished on both sides must accordingly be used.

The structure of the box blank, which is 45 formed integrally, consists in the lid 1, open center top 2, bottom 3, sides 4, end flaps 5, 6, 7, lid interlocking wing flaps 8, 9, 10, end tuck-in flaps 11 and sealing flap 12. For 50 55 effecting knocked-down assembly of the blank, as illustrated in Fig. 2, a single fold is made of the blank and flap 12 is secured adhesively to the inner face of the top 2, along the edge adjacent the lid, the end and wing flaps remaining extended.

55 60 When the box is assembled for use the body

is expanded to rectangular shape, flaps 7 are turned down, flaps 6 folded over flaps 7 and flaps 5 over flaps 6; flaps 7 are then raised and the tuck-in flaps 11 of flaps 5 are inserted under flaps 7 which are then pressed down and 60 the contents filled in the box which acts to hold flaps 5, 6 and 7 firmly interlocked under pressure of the contents. When the box is filled the lid is moved to vertical position, tabs 10 of wing flaps 9 are interlocked with 65 slots 13, the lid being then closed and tabs 14 inserted in slots 15, the wing flaps 8—9 being disposed in a fold between the lid and the top of the box. As shown in Fig. 5, the lid as closed is folded over the top of the box in 70 inverse direction to its extension in the box blank.

The end construction of the box, by reason of the novel interlocked relation of the end flaps, results in reinforced upper end edges 75 and presents closed lower end edges of the box, the arrangement being neat in appearance and providing greater strength. In ordinary boxes of this type, the lower end edges are open or unsupported, which permits the bottoms to sag under the weight of the contents of the box, which is an objectionable feature and renders the boxes unsuitable for many products.

The modification illustrated in Fig. 7 consists in placing the lid 16 at one end, and the top 17 and sealing strip 18 at the opposite end of the box blank, the rectangular shape of the box being effected by joining the sealing strip along the upper edge of the adjacent 90 side of the box. The arrangement requires printing on one side of the box blank only, and permits of folding the lid with the advertisement tab 19 in raised position with its printed face toward the front of the box, the 95 wing flaps of the lid, as here shown, being omitted.

While the improved box is here shown and described in preferred form, various modifications can be made in the arrangement of 100 the box blank and in the assembly without departing from the main structured features of the box as defined in the appended claims.

Having described my invention, I claim:

1. A paper box formed of an integral blank 105 including the lid, top, a side, bottom, opposite side and glue flap contiguous one part with another in a direct line in the order named, flaps at the opposite ends of said top, sides and bottom, the bottom flaps including mar- 110

ginal flaps, the glue flap being secured to the top adjacent its juncture with the lid, and said end flaps arranged with the top flaps innermost, the bottom flaps outermost, the 5 side flaps therebetween, and said marginal flaps tucked in along the upper end edges of the box between the top and side flaps.

2. A paper box formed of an integral blank including the lid, top, a side, bottom, opposite side and glue flap contiguous one part 10 with another in a direct line in the order named, flaps at the opposite ends of said top, sides and bottom, the bottom flaps including

marginal flaps, the glue flap being secured to the top adjacent its juncture with the lid, 15 and said end flaps arranged with the top flaps innermost and turned downward, the bottom flaps outermost and turned upward, the side flaps therebetween and turned one toward another, and said marginal flaps folded over 20 the upper edges of the bottom and side flaps and tucked in along the upper end edges of the box adjacent the top flaps.

In testimony whereof, I affix my signature.

SAMUEL BERGSTEIN.
